UNITED STATES PATENT OFFICE.

GEORGE W. DAVIS, OF LINCOLN, NEBRASKA.

DESIGN FOR A BAR FOR HOLDING PLATE-GLASS STORE-FRONTS.

57,590.

Specification for Design.

Patented Apr. 26, 1921.

Application filed November 3, 1919. Serial No. 335,554. Term of patent 14 years.

To all whom it may concern:

Be it known that I, GEORGE W. DAVIS, a citizen of the United States, residing at Lincoln, county of Lancaster, State of Nebraska, have invented a new, original, and ornamental Design for a Bar for Holding Plate-Glass Store-Fronts, of which the following is a specification, reference being had to the accompanying drawing, forming part thereof.

Figure 1 is a perspective view of a portion of a bar showing my new design.

Fig. 2, is a view of the inner face of the bar.

I claim:

The ornamental design for a bar for holding plate glass store fronts, as shown.

In testimony whereof I affix my signature.

GEO. W. DAVIS.
